COMBINED OFFSET PRINTING AND DUPLICATING MACHINE

Wolfgang Czapla, Berlin, Germany, assignor to Rotaprint
Aktiengesellschaft, Berlin, Germany

Filed May 15, 1967, Ser. No. 7,113

Claims priority, application Germany Dec. 1, 1966

Term of patent 14 years

U.S. Cl. D64—11
Int. Cl. D18—02, 03

FIG. 1

FIG. 2

FIG. 3

FIG. 4

FIGURE 1 of the drawings is a side view of a combined offset printing and duplicating machine;

FIG. 2 is an end view of the output side thereof as seen from the left of FIG. 1;

FIG. 3 is an end view of the input side thereof as seen from the right of FIG. 1; and

FIG. 4 is a top plan view thereof.

The essential features of the design reside in the portions shown in solid lines; conventional mechanical elements being shown in broken lines.

I claim:

The ornamental design for a combined offset printing and duplicating machine, as shown and described.
